FIG. 1

FIG. 3

FIG. 2

FIG. 4

FIG. 5

FIG. 8

FIG. 9

FIG. 10

FIGURE 1 is a perspective view of a bird station showing my design embodied in a bird feeder;

FIGURE 2 is a side elevational view thereof;

FIGURE 3 is a top plan view thereof;

FIGURE 4 is an end elevation view thereof;

FIGURE 5 is a bottom plan view thereof;

FIGURE 6 is a perspective view of a modified form of a bird station shown in FIGURE 1, embodied in a bird house;

FIGURE 7 is a side elevation view thereof;

FIGURE 8 is a top plan view thereof;

FIGURE 9 is an end elevation view thereof; and,

FIGURE 10 is a bottom plan view thereof.

The ends not shown in FIGURES 4 and 9 are respectively similar to the sides shown with essential differences in that the cross member of FIGURE 4 is removed and the opening in FIGURE 9 is omitted.

The sides not shown in FIGURES 2 and 7 are essentially the same as those sides shown in these figures.

I claim:

The ornamental design for a bird station, as shown and described,
